COVER CLAMP FOR PRESSURE COOKING VESSELS

Filed March 30, 1931

UNITED STATES PATENT OFFICE

FRANK W. BURPEE, OF WILMETTE, ILLINOIS, ASSIGNOR TO BURPEE CAN SEALER COMPANY, OF CHICAGO, ILLINOIS, A CORPORATION OF ILLINOIS

COVER CLAMP FOR PRESSURE COOKING VESSELS

Application filed March 30, 1931. Serial No. 526,208.

The present invention relates to the art of pressure cookers, that is, cooking vessels wherein articles are cooked under a greater or less degree of steam pressure. To render such cooking vessels efficient for the intended purpose, it is, of course, necessary to provide means for securing a substantially steam tight joint between the body and cover of the vessel. To this end, the body and cover are usually equipped with tightly inter-fitting or telescoping portions, and with external annular ribs, and a great variety of devices have heretofore been proposed for clamping these ribs together.

In one type of pressure cooker a clamping ring or band equipped with upper and lower inwardly directed flanges embracing the ribs has been proposed. Such ring is usually made in semi-circular sections hinged at one meeting end and at their other ends provided with means for tightly drawing the sections together around the ribs. My present invention is of the draw ring type, and its primary object is to provide a very simple, inexpensive and highly efficient clamping ring which will do away with the pivot joint heretofore used and at the same time will be sufficiently flexible to enable the ring to be expanded in its own plane to the extent necessary to enable the gripping flanges thereof to clear the ribs of the cover and body in applying and removing the same.

My improved cover clamp, in a selected embodiment thereof, is illustrated in the accompanying drawing, in which—

Fig. 1 is a top plan view of the vessel showing the cover and the cover clamp applied.

Fig. 2 is an enlarged horizontal section through the device for drawing together the ends of the clamping ring or band.

Fig. 3 is an enlarged transverse section taken on the line 3—3 of Fig. 1.

Fig. 4 is an enlarged vertical section taken on the line 4—4 of Fig. 2.

Referring to the drawing, I have shown in Fig. 3 a fragment of the body 10 of the vessel and a fragment of the cover 11. At the upper edge of the body 10 is an annular

external rib 12 formed with a beveled lower surface 12', and slightly above the lower edge of the cover 11 is a similar external annular rib 13 formed with a correspondingly beveled surface 13'.

Describing now my improved cover clamp, 14 designates as an entirety a one-piece circular flexible metal band. This band is formed at uniformly spaced intervals there-around with pairs of integral inwardly directed divergent upper and lower marginal flanges 15 and 16 respectively, which are designed and adapted to wedgingly embrace the opposed transversely beveled annular ribs 13 and 12 of the cover and body of the vessel in the manner clearly illustrated in Fig. 3, and when the band is tightened, to draw said ribs toward each other, thus forcing the lower end of the cover into the upper end of the body.

Referring to Fig. 1, the portions of the band between adjacent pairs of flanges are designated by 17, and in designing the clamp I have made these unflanged portions of the band sufficient in number and length to enable the band to be readily expanded to clear the ribs 13 and 12 when applying and removing the band. I have found in practice that by making the unflanged portions 17 of the band substantially equal in length to the flange themselves, and providing a considerable number of pairs of flanges, the desired result is secured in a band of sufficient weight and strength to stand the strain imposed on it without the necessity of making the band in two sections hinged together.

Describing the means herein shown for drawing together the two ends of the band, to one end of the latter is attached, as by means of an eye 18 formed in a folded and riveted end of the band and a cross pin 19 passed through said eye, a tension link consisting of straight parallel steel strips 20, between the other ends of which is rigidly mounted a nut 21 (Fig. 4), through which extends a screw 22. The inner end of the screw is rounded to fit an indented seat 23 that is formed in one face of a hollow abutment lug 24, this latter being conveniently

and cheaply formed by simply bending outwardly and thence backwardly an end portion of the band and securing the same to the band by a rivet 25.

5 In the practical use of this cover clamp, the body 10 having been charged with the articles to be cooked and a proper amount of water, the cover 11 is then applied and forced down as tightly as possible by manual pressure. The locking band is then 10 grasped by the screw 22 in one hand and a knob 26 (Fig. 1) thereon with the other hand and expanded sufficiently to enable it 15 to pass down over the cover and the ribs 13 and 12 to a position encircling the latter. On release of the expanding pressure, the band automatically contracts, its flanges embracing the ribs 13 and 12, and the link 20 carrying the screw 22 is then swung inwardly, with the screw sufficiently backed off to 20 enable the inner end of the screw to engage with the seat 23 of the abutment lug 24, and the band is then tightened by forcing the screw inwardly by its wing handle 22'. This 25 has the effect of powerfully drawing together the meeting ends of the band which, of course, at the same time draws the clamping flanges 15 and 16 inwardly on the beveled sides of the ribs 13 and 12, and this action, in turn, forces the lower end of the 30 cover tightly into the upper end of the body, producing a substantially steam-tight joint, and preventing any possibility of the cover being blown off by the internal pressure.

35 When the cooking operation is completed, the screw 22 is backed off, the link 20 is swung out clear of the abutment lug 23, and by means of the screw 22 and the knob 26, the clamping ring is spread or expanded 40 sufficiently to enable it to be lifted clear of the ribs 13 and 12, and the cover can then be removed.

The cover is provided as usual with a lifting handle 27 while the body of the vessel is equipped with the usual oppositely disposed lifting handles 28.

I claim:

1. A cover clamp for a pressure cooking vessel, comprising a one-piece circular flexible and resilient metal band formed at uniformly spaced intervals therearound with pairs of integral inwardly directed divergent marginal flanges adapted to wedgingly embrace opposed transversely beveled annular ribs on the body and cover of the vessel, the portions of said band between said pairs of flanges being sufficient in number and length to enable said band to be sufficiently expanded to clear said ribs when applying and removing the same, and means for tightly drawing together the ends of said band around said ribs.

2. A cover clamp for pressure cooking vessels, comprising a one-piece circular flexible and resilient metal band formed at uni-

formly spaced intervals therearound with pairs of integral inwardly directed divergent marginal flanges adapted to wedgingly embrace opposed transversely beveled annular ribs on the body and cover of the vessel, the flanges of each pair registering with each other, and the spaces between adjacent pairs of flanges being substantially equal in length to the flanges themselves, and means for tightly drawing together the ends of said band around said ribs.

3. A cover clamp for pressure cooking vessels, comprising a circular flexible and resilient metal band formed at spaced intervals therearound with pairs of integral inwardly directed divergent flanges adapted to wedgingly embrace opposed transversely beveled annular ribs on the body and cover of the vessel, one end portion of said band being bent outwardly and backwardly and riveted to the band to form an integral abutment lug, a link connected to the other end of said band, and a band-tightening screw mounted in said link and at its inner end abutting against said lug.

4. A cover clamp for pressure cooking vessels, comprising a circular flexible and resilient metal band formed at spaced intervals therearound with pairs of integral inwardly directed divergent flanges adapted to wedgingly embrace opposed transversely beveled annular ribs on the body and cover of the vessel, one end portion of said band being bent outwardly and backwardly and riveted to the band to form a hollow integral abutment lug, one face of said lug having an indented seat, a link connected to the other end of said band, and a band-tightening screw mounted in said link and at its inner end engaged with the seat of said lug.
